(57) CLAIM

The ornamental design for a mini roller for paint, as shown and described.

DESCRIPTION

FIG. 1 is a front, right, and top perspective view of a mini roller for paint, showing my new design;

FIG. 2 is a rear, left, and bottom perspective view thereof;

FIG. 3 is a front, right, and bottom perspective view thereof;

FIG. 4 is a front elevation view thereof;

FIG. 5 is a rear view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is another front, right, and top perspective view of the mini roller for paint of FIG. 1 in one state.

The broken lines shown in the drawings are included for the purpose of illustrating portions of the mini roller for paint that form no part of the claimed design.
